DOOR CURTAIN OR SIMILAR ARTICLE

Bruce B. Selkirk, 2 Daniel Road, La Due, Mo.

Filed Sept. 22, 1965, Ser. No. 87,528

Term of patent 14 years

(Cl. D21—6)

FIG. 1

FIG. 2

FIG. 3

FIG. 4

This application is a continuation-in-part of my co-pending application, Serial No. D. 84,965, filed April 26, 1965, and now abandoned.

I claim:

The ornamental design for a door curtain or similar article, substantially as shown and described.
